Henry Peter Glass, Chicago, Ill., assignor to Ekco
Products Company, Chicago, Ill., a corporation of Illinois

Application November 8, 1944, Serial No. 116,227

Term of patent 14 years

(Cl. D80—11)

To all whom it may concern:

Be it known that I, Henry Peter Glass, a citizen of the United States, residing at Chicago, in the county of Cook and State of Illinois, have invented a new, original, and ornamental Design for a Merchandise Display Case, of which the following is a specification, reference being had to the accompanying drawing, forming part thereof.

The figure is a front perspective view of a merchandise display case, showing my new design.

I claim:

The ornamental design for a merchandise display case, as shown.

HENRY PETER GLASS.
